Jacques E. Maisch, New York, N. Y., assignor to
Burlington Mills Corporation, Greensboro,
N. C.

Application May 1, 1953, Serial No. 24,796

Term of patent 3½ years

(Cl. D92—1)

To all whom it may concern:

Be it known that I, Jacques E. Maisch, a citizen of the United States of America, residing in New York city, county of New York, and State of New York, have invented a new, original, and ornamental Design for a Textile Fabric or Similar Article, of which the following is a specification, reference being had to the accompanying drawing, forming part thereof.

The figure on the drawing is a face view of a textile fabric or similar article showing my new design.

In the drawing, a full width of the fabric is shown; the design being repeated vertically as indicated by the dot and dash lines containing the design unit.

I claim:

The ornamental design for a textile fabric or similar article, substantially as shown and described.

JACQUES E. MAISCH.
